(57) **CLAIM**

The ornamental design for a bag, as shown and described.

DESCRIPTION

FIG. 1 is a front, left side perspective view showing our new design for a bag;

FIG. 2 is a front elevation view thereof;

FIG. 3 is a back elevation view thereof;

FIG. 4 is a top elevation view thereof, with the handles shown extended towards the sides;

FIG. 5 is a bottom elevation view thereof, with the handles shown extended towards the sides; and,

FIG. 6 is a left side elevational view thereof.

The broken lines shown in the drawings depict portions of the bag that form no part of the claimed design.

The letter “T” encircled by the letter “C” forming part of the claimed design, shown in FIGS. 1 through 3, is a registered trademark of Telfar LLC.

1 Claim, 5 Drawing Sheets
